UNITED STATES PATENT OFFICE.

ELMER L. SAVOLD, OF HILLS, MINNESOTA.

AUTOMATIC CROSSING GATE.

Application filed March 27, 1926. Serial No. 97,826.

This invention relates to railway crossing gates and more particularly to mechanisms connected therewith for automatically opening and closing the gates by means adapted to be operated from the cow-catcher or advanced portion of a railroad engine or the like.

It is an object of this invention to provide railroad crossing gate control means adapted to be automatically opened and closed by a train.

It is also an object of this invention to provide railroad gates having mechanisms connected therewith for opening and closing the same at predetermined times, said means adapted to be governed by a train as it approaches a crossing and leaves the same.

It is furthermore an object of this invention to provide railroad crossing gates with mechanisms adapted to be operated by a passing train to cause opening and closing of the gates at predetermined times.

It is an important object of this invention to provide a railroad crossing gate control mechanism adapted to be operated by means of a shoe on the cow-catcher or fender of an engine, whereby the mechanism is first adapted to be operated to cause opening of the gates with the approach of an engine and then cause automatic closing of said gates as soon as the engine has passed the crossing and comes into operating contact with the gate closing control mechanism.

Other and further important objects of this invention will be apparent from the disclosures in the specification and the accompanying drawings.

This invention (in a preferred form) is illustrated in the drawings and hereinafter more fully described.

On the drawings:

Figure 1 is a fragmentary top plan view of a railroad track and road crossing, said crossing being equipped with gates adapted to be automatically operated by control mechanisms embodying the principles of this invention and associated with the tracks.

Figure 2 is an enlarged fragmentary side elevation of the track taken on line II—II of Figure 1, showing a fragmentary portion of an engine cow-catcher or fender and furthermore indicating in dotted lines the operation of a control device.

Figure 3 is an enlarged fragmentary detail section taken longitudinally through one of the shock absorbing mechanisms forming part of the system.

Figure 4 is an enlarged transverse vertical section taken on line IV—IV of Figure 1, showing a portion of the engine cow-catcher equipped with a control shoe.

Figure 5 is an enlarged fragmentary vertical section of the lower portion of a crossing gate, showing parts in elevation.

Figure 6 is a fragmentary sectional view taken on line VI—VI of Figure 5.

As shown on the drawings:

The reference numeral 1 indicates a cross road over which a railroad track is laid. The track comprises the ordinary pair of steel rails 2 and the railway ties 3. At spaced intervals from the road crossing are longer ties 4, 5 and 6 for a purpose herein-after more fully described. As illustrated in Figures 2 and 4, the reference numeral 7 indicates a fragmentary portion of a railroad engine cow-catcher or fender. Mounted on one side of the cow-catcher is a control shoe 8. Mounted on opposite sides of the track and on diagonally opposite sides of the road 1 are railroad crossing gates 9 each of which is supported on a hollow pedestal 10 provided with a transverse bearing sleeve 11 in which is journalled a shaft 12 for supporting the gate 9. The gate 9 may be of any desired construction carrying the counterweights 13 as shown in Figure 5. Secured on the gate shaft 12 in the pedestal 10 is a crank arm 14 to the end of which is pivotally connected a connecting rod 15. The lower end of the connecting rod 15 is pivotally connected to a bell crank 16 which is rotatably supported on a rod or shaft 17 mounted in the lower portion of the pedestal 10. Pivots connected to the second arm of the bell crank 16 is one end of a connecting bar or rod 18 which passes out of the pedestal through a suitable opening 19. The outer end of the connecting bar 18 is pivotally connected to the long arm 20 of an intermediate bell crank having a short arm 21. The intermediate bell crank 20—21 is pivotally supported on a vertical peg or shaft 22 projecting from the ground or from any other suitable support.

The outer ends of the two short bell crank arms 21 are pivotally connected to a

main connecting rod or bar 23 which, as clearly illustrated in Figure 1, slidably extends transversely through a suitable conduit or opening in the cross road 1. One 5 end of the main connecting rod 23 is connected to one end of a slidably yoke 24 which slidably projects from a shock absorbing cylinder or housing 25 which is securely mounted on the extending ends of the two 10 railway ties 4. A second yoke 26 is slidably mounted in the housing 25 with the outer end of said yoke 26 projecting from the end of the housing and connected with a connecting bar or rod 27. Mounted in the 15 shock absorbing housing 25 between the two telescoping yokes 24 and 26 is a heavy control spring 28. The other end of the connecting rod 27 is pivotally connected to a short bell crank arm 29 which is secured on the 20 outer end of a main operating shaft 30 which is mounted transversely of the track below the rails 2 as clearly illustrated in Figures 1 and 4. Also secured to the 25 main control shaft 30 to the outside of the rails 2 are two upwardly directed long bell crank arms 31. The upper ends of the long bell crank arms 31 are pivotally connected to a pair of control rails 32, the ends of which are curved downwardly 30 at 33. The two control rails 32 are positioned on opposite sides of the track rails 2 and have the ends nearest the road crossing 1 pivotally connected to supporting arms similar to the long bell crank 35 arms 31. It will be noted that the main control shaft 30 together with the arms 29 and 31 connected thereto form a main control bell crank mechanism which is adapted to be operated by means of control rails 32 40 when said control rails are operated by means of a shoe 8 carried by a railway engine fender as hereinbefore described.

Connected to the second end of the main connecting rod 23 is one arm of a fulcrumed 45 lever 34 which is pivotally supported on the extended end of the railway tie 5. The other end of the fulcrumed lever 34 is connected to the yoke member 24 of a gate shutting mechanism. As illustrated in Figure 1, the automatic gate opening mechanisms are represented as a whole by the reference character A, while the automatic gate closing mechanisms on the opposite side of the road are represented as a whole by the 50 reference character B.

The four control rails 32 are provided two on each side of the cross road 1 for the purpose of permitting the operation of the automatic gate operating mechanisms by an 60 engine or car approaching from either direction. When the control rail 32 of the gate opening mechanism A is in its elevated position as shown in Figure 2, the control rail 32 of the gate shutting mechanism B 65 is in a lowered position equivalent to the

dotted line position of the control rail 32 illustrated in Figure 2. It will thus be seen that the two pairs of control rails 32 positioned upon opposite sides of the main railroad track permit the gate control mechanisms to be operated and to be opened and closed automatically when a train approaches the cross road from either direction. 70

The operation is as follows:

With the automatic crossing gate mechanisms mounted in the positions illustrated in Figure 1 and with the crossing gates 9 in their raised position, an engine approaching from the left looking at Figure 1 and carrying a control shoe 8 on the cow-catcher 75 or fender, or on any other advanced portion of the advancing vehicle, the downwardly curved arm 33 of one of the control rails 32 is first engaged by the shoe 8 on the approaching engine said shoe acting to move the control rail 32 from the full line position of Figure 2 into the dotted line position. This operation of the control rail 32 actuates the long bell crank arms 31 thereby causing the short bell crank arm 29 80 to swing from the full line position of Figure 2 into the dotted line position. This movement of the short bell crank arm 29 causes operation of the primary connecting rod 27 which in turn actuates the shock absorbing mechanism within the housing 25 before the movement is transmitted to the secondary connecting rod 23. With the 85 operation of the secondary connecting rod 23 in a direction opposite to that of the approaching train, both of the bell cranks 20-21 are operated, thereby causing simultaneous operation of the gate control rods 18 which when operated actuate the bell cranks 16 and the connecting rods 15 within 90 the gate pedestals 10 thus causing operation of the crank arms 14 to cause the gates 9 to be gradually swung downwardly into closed position transversely of the cross road 1 and on opposite sides of the track. 100

When the control rail 32 of the gate opening mechanism A is moved into its lower position as shown in dotted lines in Figure 2, the control rail of the gate closing mechanism B is moved from a lowered into a 105 raised position similar to the full line position of the control rail 32 illustrated in Figure 2. It will thus be noted that when one of the control rails is lowered, the one on the opposite side of the road is raised and vice versa. 110

As soon as the cow-catcher of the advancing engine crosses the road 1 and approaches the second control rail on the opposite side of the road, the shoe on the cow-catcher moves into engagement with the control rail 32 of the gate closing mechanism B, thereby tending to move the same from a raised to a lowered position, thus causing a reverse 125 operation of the mechanisms A and B to 130

take place, resulting in the automatic raising or opening of the gates 9.

It will thus be seen that the crossing gates 9 are adapted to be automatically lowered 5 and raised by means of the control shoe 8, which control may be carried on any convenient portion of an approaching engine, car, or the like. It will also be understood that the gate control mechanisms A and B 10 may be positioned at substantial distances from the cross road to facilitate proper operation of the gates in due time. The two sets of control rails 32 positioned on opposite sides of the road and on opposite sides of 15 the rails 2 afford an arrangement whereby the mechanisms A and B may be automatically operated at predetermined times by a train or vehicle approaching from either direction.

20 I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. The combination with a railroad track and a cross road, of crossing gates positioned on opposite sides of said road, gate opening mechanisms on one side of said road, gate closing mechanisms on the opposite side of said road, control shoes connected with said mechanisms and mounted to raise and lower on opposite sides of said road in the path of movement of an advancing engine, a connecting member at one side of the track between said mechanisms, arranged to elevate the shoes at one side of the road when 30 the shoes at the other side of the road are depressed, and means carried by the engine adapted at predetermined times to first coact with one of said control shoes to cause automatic closing of the gates and then adapted 35 to be brought into coacting engagement with the control shoe on the opposite side of the road to cause automatic opening of said gates.

2. In a railway gate apparatus including 40 a pair of gates mounted at opposite sides of a track, and also upon opposite sides of

a roadway across the track, gate operating mechanisms of similar construction at opposite sides of the track and the roadway, a connecting member along one side of the track between said mechanisms having operative connections at spaced points and of a similar nature with the said gates, shock-absorbing means between said gate operating mechanisms and the said connecting member, and engine actuated shoes at opposite sides of the track and the roadway and linked to said gate operating mechanisms, said shoes at one side of the roadway being in elevated position when the shoes at the opposite side of the roadway are depressed. 45

3. In a railway gate apparatus, a pair of balanced gates disposed at opposite sides of a track, a connecting bar paralleling the track, connections of a similar nature between the said gates and spaced points of the connecting bar, a pair of spaced-apart gate operating mechanisms, one of which is directly connected to one end of said connecting bar, a bell crank between the other 50 end of the connecting bar and the other operating mechanism, and engine actuating shoes linked to said operating mechanisms and so arranged that the shoes of one operating mechanism are in actuated position when the shoes of the other operating mechanism are in normal position and vice versa.

4. In a railway gate apparatus, a pair of balanced gates, similar connections for closing and opening each of the gates, including connecting bars in spaced-apart parallel relation, a third connecting bar at right angles to the first named connecting bars and having at spaced points bell cranks connecting the same with the first mentioned 55 connecting bars, a pair of gate operating mechanisms, one of which is directly connected to one end of the third connecting bar, a bell crank connecting the opposite end of the third connecting bar with the other 60 gate operating mechanism, and engine actuated shoes operatively connected to the said gate actuating mechanisms for the purpose set forth.

In testimony whereof I have hereunto subscribed my name.

ELMER L. SAVOLD.
